FLUID COOKING WITH CRACKING OF MORE REFRACTORY OIL IN THE TRANSFER LINE

Charles L. Persyn, Concord, Calif., assignor to Tidewater
Oil Company, Los Angeles, Calif., a corporation of
Delaware

Filed Mar. 21, 1962, Ser. No. 181,406
4 Claims. (Cl. 208—53)

This invention relates to an improved petroleum refining process involving improvements in fluid coking for upgrading of heavy oils. More specific aspects of the invention relate to novel relationships between catalytic cracking and fluid coking.

As is well known in the art, the fluid coking process uses a fluid coking vessel or "reactor" and an external heating vessel, e.g., a fluid bed burner. A fluid bed of solids, preferably coke particles produced by the process having a size in the range of about 40 to 1000 microns, is maintained in the coking zone by the upward passage of a fluidizing gas, usually steam. The temperature of the bed is maintained at about 950° F. by circulating solids (coke) to the heating vessel (coke burner) and back. The heavy mineral oil to be converted is injected into the fluid bed and upon contact with the hot solids undergoes pyrolysis evolving lighter hydrocarbon vapors and depositing coke on the solids. The turbulence of the fluid bed normally results in substantially isothermal conditions and in thorough and rapid distribution of the heavy injected oil. Product vapors, after heavy entrained solids are removed, are withdrawn overhead from the coking vessel and sent to a scrubber and fractionator for cooling and separation. Generally, a stream of the coke particles is continuously withdrawn from the coking vessel or reactor and passed to the burner, where some of its is burned to heat the remainder, and heated coke is continuously recirculated to the reactor.

In the scrubber the heavier constituents of the effluent product vapor are condensed, usually with the aid of a quench oil, which may be at least a portion of the heavy oil fed to the coking reactor, in order to remove any coke particles and other undesirable heavy elements in the form of a slurry, this slurry being then fed to the coking reactor for further treatment. From the top of the scrubber, the cracked vapors pass to the fractionator, where they are separated into gas, gasoline, and a light gas oil. The light gas oil is normally used as charge stock for catalytic cracking of any of several types, including the more recent hydrocracking.

From a point near the top of the scrubber there is also withdrawn a stream of heavy gas oil, which, by reason of its nitrogen content, ash content, or aromaticity, is decidedly unsuitable as a catalytic cracking feed stock because it fouls the catalyst. Heretofore, this heavy gas oil has been used principally as an element of fuel oil. However, fuel oil is not nearly such a profitable product as gasoline; so attempts have been made to recycle this heavy gas oil through the coking reactor in the hope that it could be reduced completely to lighter distillates. As conversion of this material must take place in the vapor phase because its boiling range is lower than that of the heavy feed stock, such recycle operation is not attractive. Because the coking temperature in the coking reactor is relatively low, high conversion of the refractory heavy gas oil is difficult to obtain and apparently less than 5%

2

of it is converted by such recycle. This results, then, in excessive recycle rates. This difficulty cannot economically be circumvented by increasing the coking temperature in the coking reactor, because such an increase would result in excessive thermal degradation and loss of the light distillate products.

It has also been suggested that this heavy gas oil be cracked at very high temperatures (e.g., 1200° F. to 1600° F.) to produce gases, but this requires separate reactors and results in products that generally are less valuable than gasoline and catalytic cracking charge stock.

I have found, however, that by introducing the heavy gas oil into the transfer stream of coke coming from the coke burner to the coking reactor, in which stream the temperature is higher than in the reactor bed, being in the neighborhood of 1100° to 1150° F., a considerable amount of the heavy gas oil can be converted to gasoline, light gas oil suitable for catalytic cracking, and effluent gases, while certain other portions take on characteristics like that of the oil in the recycle slurry, so that further recycle, possibly until extinction, becomes feasible.

Another petroleum process which has achieved great importance is that of catalytic cracking, including the more recently developed hydrocracking. Catalytic cracking units require a charge stock much higher in grade than that of fluid coking units. In fact, fluid coking units are customarily added to refineries for the purpose of handling residuum which would be certain to foul catalytic cracking units and which would give very poor results in other types of cracking units. As already mentioned, the light gas oil produced by a fluid coking unit is good charge stock for the catalytic cracking unit, and it is produced in even greater quantity by the use of the present invention. Other suitable charge stocks come from other portions of the refinery.

In the catalytic cracking unit most of the charge stock is upgraded to gasoline and other high grade products. The remainder, a heavy fraction containing (in a fluidized catalytic cracking process) entrained catalyst, is settled out and a clarified portion is decanted off. This portion, known as decanted oil, is fairly low-grade stock, which heretofore has been used mainly as fuel oil. It has many of the characteristics of coker heavy gas oil and the effects of adding it to a fluid coker are similar to those obtained from adding heavy coker gas oil.

I have found that decanted oil from a fluid catalytic cracking unit can also be upgraded by charging it to the hot coke line.

Thus, the invention links fluid coking and fluid catalytic cracking in a new way and accomplishes a novel type of recycle and cracking for both the decanted oil from the catalytic cracking unit and the heavy gas oil obtained from the coker unit.

Other objects and advantages of the invention will appear from the following description of a preferred embodiment thereof.

The drawing is a diagrammatic representation of processing steps incorporating the principles of the present invention, and illustrates diagrammatically both a fluid catalytic cracking unit and a fluid coking unit operating in conjunction with each other. For purposes of simplicity, most of the steam inlets, pumps, blowers, coolers, and similar details well known to the art have been omitted.

The drawing illustrates a fluid coking reactor 1 and

a coke burner 2. In the coke burner 2 coke is burned to provide heat for the coking reactor 1 and hot coke is returned to the coking reactor 1 through a hot line 3, preferably and normally entering the upper part of reactor 1 as indicated in the drawing. To the coking reactor 1, which is at a temperature of between 925° and 1000° F., a charge stock of residuum and recycled slurry enters below the hot coke (see the drawing) from lines 4 and 5 via a suitable manifold system. The injected oil contacts a bed 6 of fluidized coke and undergoes pyrolysis, evolving lighter hydrocarbon vapors and depositing additional coke on the coke particles.

Fluidization gas, e.g., steam, is injected at numerous points, indicated in the drawing by lines 7 and 8, to maintain fluidization of the coke particles and to effect transfer of coke from the burner 2 to the reactor 1. Coke particles, after having been stripped of entrained hydrocarbons and after having oversize particles screened out and removed through a line 9, are withdrawn from the base of the vessel 1 and sent to the coke burner 2 through line 10, to which steam or air is supplied as by a line 11. Coke in excess of that needed for burning and recirculation to the reactor 1, where it supplies heat for the exothermic coking reaction, is withdrawn from the burner 2 through a line 12.

From the reactor 1, the vaporous conversion products are withdrawn overhead through cyclone separators 13 which remove fine particles of entrained coke and return them to the reactor 1. From the cyclones 13, the effluent passes up into a scrubber 14, to which some or all of the fresh feed may be fed as quench oil through a line 15 and from which a slurry is withdrawn through a line 16 for recycle either to the quench line 15 (after settling in a settler 17 and cooling in a heat exchanger 19) or to the recycle line 5 or both. From the scrubber 14, the uncondensed effluent passes overhead through a line 18 to a fractionator unit 20 where various fractions are taken off, such as gases and gasoline vapor in line 21, a light gas oil (boiling below 630° F.) in line 22, and a heavy portion that is recycled as reflux by line 23. Near the top of the scrubber 14, heavy gas oil (mostly boiling in the 600°-900° F. range) is withdrawn by a line 24.

Heretofore, the heavy gas oil withdrawn through the line 24 has been passed to storage (represented by a tank 25) for disposal as fuel oil. In the present invention valves 26 and 27 may be installed in the line 24 and part or all of the heavy gas oil may be sent through the valve 27 and a line 28 into the hot coke riser line 3 at a point 30 where the coke is about 1100° to 1150° F. The oil entering the line 3 at the point 30 vaporizes almost instantly and acts as a fluidizing vapor so that much less, if any, steam need be added through the line 8 or elsewhere in the line 3 in order to impart proper movement to the coke fluidized in the line 3. While passing with this very hot coke through the line 3 into the reactor 1, this heavy gas oil—which cannot be cracked by contact with the coke in the reactor 1—is cracked to yield additional light gas oil, gasoline, gases, and a residue of heavier gas oil, much of which becomes part of the recycle slurry and may be capable of cracking when recycled with it. Possibly, the very volatility of the heavy gas oil combines with its refractoriness to prevent cracking when it is fed to the coking reactor bed by lessening the dwell time there; surely there is no such effect on dwell time when it is fed to the line 3, since it has to pass through that line. At any rate, the desired cracking of a substantial part is attained by this invention. Another part goes into the heavy gas oil line 24 again for a recycle to the line 3 or to the fuel oil storage unit 25.

As illustrated in the drawing, the light gas oil withdrawn through the line 22 is charged via lines 31 and 32 to a fluidized catalytic cracking reactor 33 along with other catalytic cracker charge stock. Catalyst from a regenerator 34 is fed in a fluidized condition through the line 32 to the reactor 33, and is returned through line 35

from the reactor 33 to the regenerator 34. The effluent from the reactor 33 passes through a line 36 to a fractionator 37, whence gas and gasoline are taken off through a line 38, light gas oil through line 39, and heavy "catalytic" gas oil through line 40 (having quite different properties from the heavy coker gas oil in line 24). A bottoms fraction containing catalyst fines which were entrained in the vapors in the line 36 is passed by a line 41 to a Dorr clarifier 42, whence a decanted oil is withdrawn through a line 43. This decanted oil (having a boiling range substantially between 600° and 900° F.) has heretofore been sent to fuel oil such as to the storage tank 25 through line 45. According to a specific embodiment of this invention, a portion at least of this decanted oil is diverted by valves 46 and 47 into the line 28 and is charged into the hot coke line 3, where it is cracked in a reaction similar to that of the heavy gas oil which it resembles in many ways. If desired, the two may be charged as a mixture.

Turning now to a specific example, a residuum feed stock coming into the coking unit 1 through the charge line 4 may be as follows:

TABLE I

Properties of Feed Stock Residuum Charged to the Coking Reactor	
API gravity	8.0
Conradson carbon, wt. percent	14.3
Surfur, wt. percent	2.7
A.S.T.M. distillation (D-1160), ° F.:	
IBP	614
10%	891
33%	1000

The conditions in the coking reactor 1 are shown in Table II.

TABLE II

Operating Conditions in Coking Reactor	
Pressure, p.s.i.g.	12
Feed inlet temperature, ° F.	620
Reactor temperatures, ° F.:	
Dense phase	970
Dilute phase	1015
Burner temperature, ° F.	1150
Vapor holding time, total seconds	18
Coke in reactor, tons	800
Coke circulation, tons/minute	45 to 55

The heavy gas oil effluent (line 24) has the following properties:

TABLE III

Properties of the Heavy Gas Oil Effluent	
Gravity, ° API	10.7
Conradson carbon, wt. percent	0.83
Pour point, ° F.	70
Sulfur, wt. percent	1.77
Nitrogen, wt. percent	0.97
Viscosity:	
SSF at 122° F.	36
SSU at 210° F.	55.6
Metals, p.p.m.:	
Vanadium	0.014
Nickel	0.14
Copper	0.10
Distillation, ° F. (distilled at 1 mm. of Hg Cor- rected to 760 mm. of Hg):	
IBP	527
10%	684
50%	786
90%	873

For the purpose of comparison in this example, this heavy gas oil is divided into three samples, and, at separate times, each sample is separately charged to the coking system. Sample 1 is processed in the reactor 1, and Samples 2 and 3 are processed in the line 3, all under the conditions given in Table IV, where the Samples 1, 2, and 3 are compared with a "Sample 0" representing the conventional processing in which the heavy gas oil is not recycled at all.

TABLE IV

Fluid Coking of Heavy Gas Oil of Table III,
Operating Data

Sample No.	0	1	2	3
Fresh Feed Rate, b./d.	42,000	42,000	42,000	42,000
Recycle Rate, Vol. Percent of Fresh Feed	40.0	40.0	40.0	40.0
Heavy Coker Gas Oil:				
To Hot Coke Riser Line, b./d.	0	0	5,000	5,000
To Coker Reactor, b./d.	0	5,000	0	0
Recycle Rate, Considering Heavy Coker Gas Oil as Recycle, Vol. Percent of Fresh Feed	40.0	51.9	51.9	51.9
Reactor Holdup, Tons of Coke	800	800	800	800
Reactor Temperature, Bed, ° F.	970	970	970	970
Reactor Temperature, Vapor Phase, ° F.	1,015	1,015	1,015	1,015
Reactor Pressure, p.s.i.g.	12	12	12	12
Burner Temperature, ° F.	1,150	1,150	1,160	1,180
Temperature at Hot Coke Riser Line, ° F.	1,150	1,150	1,150	1,100
Coke Burned, Tons/Day	520	520	520	520
Steam to Hot Coke Transfer Line, lbs./hr.	49,000	50,000	32,000	30,000

The coke circulation rate is in all four cases between 45 and 55 tons per minute, the addition of up to 5000 b./d. of heavy gas oil apparently not requiring a material increase in burner temperature or circulation rate of coke.

The yields of these three samples are as follows:

TABLE V

	Samples			
	Normal Operation 0	1	2	3
Dry gas (C ₂ Minus) M s.c.f./d.	27,090	27,790	34,390	31,025
Total Propanes, b./d.	2,814	2,854	3,824	3,354
Total Butanes, b./d.	1,974	1,999	2,444	2,269
Gasoline (39° F. at 90% Dist.) b./d.	12,222	12,372	12,892	13,002
Light Gas Oil (600° F. at 90% Dist.) b./d.	4,578	4,738	4,703	4,983
Heavy Gas Oil (630° F. plus), b./d.	13,692	113,282	110,429	111,207
Coke, gross, M lbs./d.	3,646	3,680	3,806	3,692

¹ Net after deducting the 5,000 b./d. heavy gas oil recharged.

From Table V it will be seen that straight recycling of heavy gas oil to the coking reactor (Sample 1) accomplishes little, while the introduction of the heavy gas oil into the hot coke riser in accordance with the invention (Samples 2 and 3) produces good yields of desirable products.

It will be noted especially that gasoline and light gas oil, suitable for catalytic cracking charge, are increased a substantial amount by the invention and that the heavy gas oil has been substantially reduced.

It is also to be noted that a transfer line temperature of 1100° F. affords substantially better yields of gasoline and light gas oil than a temperature of 1150° F., indicating that further increases would be even less desirable.

As a further example, consider a decanted oil from catalytic cracking, having the following properties:

TABLE VI

Charge Stock Properties of Decanted Oil

Gravity, ° API	16.3
Conradson carbon residue, wt. percent	1.75
Viscosity:	
SSU at 100° F.	92.3
SSU at 210° F.	37.4
Sulfur, wt. percent	1.13
Nitrogen, wt. percent	0.16
Ash, wt. percent	Nil
Distillation (corrected to 760 mm. of Hg):	
IBP, ° F.	458
10%	594
50%	721
90%	812

The decanted oil of Table V is divided into three samples, Sample 4 being fed at one time to the coking reactor, Sample 5 at another time to the line 3 at 1150° F. and Sample 6 at still another time to the same line 3 at 1100° F., the temperature being controlled by small changes in the burning and recycle rates of the coke. Yields from the three samples are shown in Table VII, together with the yields from normal operation, "Sample 0," in which there is no addition of any decanted oil.

TABLE VII

Fluid Coking Yields of Samples 4, 5, and 6

	Normal Operation	Samples		
		4	5	6
Dry Gas (C ₂ Minus) M s.c.f./d.	27,090	27,665	33,600	30,450
Total Propanes, b./d.	2,814	2,844	3,738	3,276
Total Butanes, b./d.	1,974	1,994	2,436	2,226
Gasoline (39° F. at 90% Dist.), b./d.	12,222	12,317	12,516	12,558
Light Gas Oil (600° F. at 90% Dist.), b./d.	4,578	4,723	4,703	4,620
Heavy Gas Oil (630° F. Plus), b./d.	13,692	18,297	15,442	16,192
Coke, Gross, M lbs./d.	3,646	3,690	3,844	3,753

I claim:

1. In a fluid coking process wherein a heavy hydrocarbon charge oil is cracked to lower boiling hydrocarbons by contact with a dense fluidized bed of heated coke particles in a coking zone and the bed is maintained at coking temperature by circulation of coke particles from said bed to a burning zone wherein a portion thereof is burned to heat the remainder substantially above the temperature of said bed and thus heated coke particles are returned to said bed through an elongated transfer zone,

the method of simultaneously cracking a heavy oil more refractory and more volatile than said charge oil which comprises

introducing only said more refractory oil into said transfer zone to travel therethrough in contact with heated coke particles therein, for a distance sufficient that said more refractory oil is cracked therein at a temperature substantially above that to which said charge oil is subjected.

2. A process as in claim 1 wherein the more refractory oil is a heavy gas oil.

3. A process as in claim 1 wherein the more refractory oil is a decant oil.

4. A process as in claim 1 wherein the more refractory oil is a mixture of a heavy gas oil and a decant oil.
